UNITED STATES PATENT OFFICE.

JAMES JESSEN, OF MINNEAPOLIS, MINNESOTA, ASSIGNOR OF ONE-HALF TO JAMES A. McNULTY, OF MINNEAPOLIS, MINNESOTA.

GAS-ENGINE.

1,325,295.

Specification of Letters Patent. Patented Dec. 16, 1919.

Application filed March 21, 1916. Serial No. 85,572.

To all whom it may concern:

Be it known that I, JAMES JESSEN, a citizen of the United States, residing at Minneapolis, in the county of Hennepin and State of Minnesota, have invented certain new and useful Improvements in Gas-Engines, of which the following is a specification.

My invention relates to gas engines for carbureting air and delivering said carbureted air to the explosion chambers of the engine.

It is the object of my invention to provide in connection with a gas engine, preferably of the two-cycle type and having a pair of cylinders, means which, in cooperation with the carbureter or primary air mixing device, will thereafter cause the mixture of fuel and air coming from said carbureter to be alternately and repeatedly discharged into passageways or chambers which are alternately in vacuum and under compression and which are heated by the circulating medium of the cooling system of the engine.

It is a further object of my invention to provide in combination with the means for so controlling the carbureted mixture, means for injecting air under pressure into the explosion chamber at the time of and following exhaust to force the burnt gases out of the chamber and replace the same with fresh air, into which the above referred to carbureted mixture will be injected at a proper point in the cycle of operations.

The full objects and advantages of my invention will appear in connection with the detailed description thereof and are particularly pointed out in the claims.

In the drawings illustrating the application of my invention in one form,

Figure 1 is a sectional elevation through one of the explosion cylinders, at right angles to the crank shaft. Fig. 2 is a sectional elevation on line 2-2 of Fig. 1. Fig. 3 is a sectional plan view in the planes represented by lines a-a and z-z of Fig. 1 and along the irregular line a-z of Fig. 2. Fig. 4 is a sectional plan view taken in the planes of the lines y-y and x-x of Fig. 1 and along the line y-x of Fig. 2. Fig. 5 is a sectional elevation taken on the line W-W of Fig. 1 showing the carbureter. Fig. 6 is a sectional plan view taken on the line V-V of Fig. 5. Fig. 7 is a plan sec-

tional view of a portion of the device taken on line N-N of Fig. 5.

As illustrated, a pair of engine cylinders 10 and 11 of a well-known type have operative therein pistons 12 and 13 which are connected by crank rods 14 and 15 with a crank shaft 16. Immediately at the rear of cylinders 10 and 11 are other cylinders 17 and 18 which have therein compound pistons having upper portions 19 and 20 and lower portions 21 and 22, the respective portions being separated by central partitions 23 and 24, which partitions are formed with tubular openings 25 and 26 within which slide tubular members 27, 28 secured to piston portions 19 and 20, respectively, and opening at their bottoms into chambers 29 and 30 formed between the piston portion 21 and partition 23 and piston portion 22 and partition 24. Rods 31 and 32 connect piston portions 19 and 21 and 20 and 22, respectively, and piston rods 33 and 34 connect the piston portions 21 and 22 with a crank shaft 23 journaled in the crank casting 24 in parallel relation with the engine crank shaft 16 and operated from said engine crank shaft by spur gears 35 and 36. The combustion chambers of cylinders 10 and 11 and the upper portion of the cylinders 17 and 18 are inclosed in an outer water-jacket casing 37 which discharges through an enlarged pipe 38 at the top.

The cylinders 10 and 11 are each provided with a multiplicity of ports 39 which communicate with the outside air behind a flanged lip 40 which is offset and cast downwardly from the cylinder wall, the ports 39 being just above the opening into the crank case which is thus always kept at atmospheric pressure. The pistons 12 and 13 alternately open and close the set of ports 39 in the different cylinders so that one or the other of such sets is always open. Each of the pistons 12 and 13 is also provided with a port 41 back of a flange lip 42 cast upwardly from the inner wall of said pistons, and having a function which will be hereinafter pointed out.

The cylinders 10 and 11, as clearly shown at the left of Fig. 4, are each provided with a multiplicity of exhaust ports 43 discharging into a single exhaust passageway 44 and a series of inlet ports 45 which discharge into downwardly extending passageway 46.

or 47 that opens through an enlarged port 48 into chamber 29 or 30 immediately below the stationary partition 23 or 24. A second series of inlet ports 49 formed in 5 connection with passageways 50, preferably directed upwardly toward the spark plugs 51, as indicated in Fig. 1, connect the combustion chambers within cylinders 10 and 11 with the interior of cylinders 17 10 and 18. The inlet ports 45 and 49 and exhaust ports 43 are controlled by the power pistons 12 and 13. It will be noted that both sets of inlet ports 45 are in substantially the same plane as exhaust ports 43. 15 The upper edges of said exhaust ports are farther advanced than the upper edges of said inlet ports so that the exhaust ports will open just before the opening of inlet ports 45, when air compressed in chamber 20 29, or 30, will be forced into the combustion chamber, being deflected upwardly by a lip 52 on the piston head, so that such air will replace the gases of combustion in the combustion chamber. From an inspection 25 of Fig. 1 it will be seen that the compound piston form of sections 19 and 21 or 20 and 22 move concurrently with the power pistons but considerably in advance thereof, so that the outward movement of the compound 30 piston 19—21 or 20—22 is considerably advanced when the inward or expansion stroke of the power piston is nearing completion. This movement brings the port opening of passageway 53 communicating with the interior 35 54 of tubular member 27 into communication with port passageway 50 just after the opening of ports 45 and until after the closing of said ports.

Air will thus be forced from chamber 29 40 (or 30) into the explosion cylinder not only through ports 45 but through the ports 49 higher up in the cylinder and during the compression stroke of the power piston.

The construction of the compound valve 45 pistons heretofore referred to is such that chambers 55 and 56 are formed above partitions 23 and 24. The chambers on opposite sides of these partitions alternately become suction and compression chambers and 50 these chambers are connected as shown in Fig. 2, the upper chamber 55 of one cylinder being connected with the lower chamber 30 of the other cylinder by a passageway 57 and the upper chamber 56 being connected with the lower chamber 29 by a similar passageway 58 (indicated in dotted lines). 55 From this arrangement it will be seen that during the down stroke of compound piston 19—21 and the concurrent upstroke of compound piston 20—22 the connected chambers 29 and 56 are in vacuum or in suction and the connected chambers 55 and 30 are compression chambers; and that the reverse 60 condition will be true with the reverse movement of the pistons, but chamber 29

is open to atmosphere through port 48, passageway 46, cylinder inlet ports 45, piston port 41 and cylinder ports 39, by which means air is supplied to both suction chambers as well as to the crank case and is 70 caused to pass through and beneath the power piston, thereby withdrawing heat from such parts and heating the air to be injected into the cylinder, the piston being provided with a ribbed under surface as 75 indicated at 59 in Fig. 1.

A most important feature of my present invention consists in the manner in which fuel is mixed and supplied to the explosion cylinders after the same have been charged 80 with air as hereinbefore pointed out. The fuel oils employed in connection with internal combustion engines are of varying characters as regards the point at which such oils give off or distil hydrocarbon 85 gases. The relatively volatile oils, like gasoline, give off these gases more readily at ordinary temperatures and at lower temperatures than the heavy oils, such as kerosene; but it is true of all fuel oils that they 90 comprise in fact a mixture of the hydrocarbon products having different points of distillation. In all primary carbureters, therefore, as now employed there is a tendency 95 for some heavier and less volatile particles of the fuel oil to be carried along in an ungasified condition through the carbureter and manifold and into the explosion chamber of the engine. This results in an imperfect explosive mixture, imperfect combustion and consequent waste 100 of fuel oil. A carbureting system which makes practicable the formation of all of the hydrocarbons of any given fuel oil which may be employed into true gases 105 which become thoroughly intermingled with the air to form the explosion mixture, is in the highest degree desirable in producing the greatest possible efficiency of an internal combustion engine. The method 110 and means employed by me in carbureting the fuel oil and supplying the same to the explosion cylinder effect the above indicated result.

Referring to Figs. 5 and 6, a primary 115 fuel feeding mechanism 60 having therein a float-controlled needle valve mechanism 61 is provided which may be of any well-known form of construction at present used in so-called carbureters. The member 60 120 is preferably secured integrally with a casting section 64 having a downwardly-curved air passageway 65 communicating with an air passageway 62 which extends across the top of the casing inside of the water-jacket, 125 as clearly shown in Figs. 1, 2 and 5, and connects with an air-inlet opening 63 outside of said casing. The air passing through passageway 62 immediately above the explosion cylinders 10 and 11 is thus pre- 130

heated before passing into the curved passageway 65 and tends to heat the body of fuel oil 66 in member 60 which is in contact with the lower curved wall of passageway 65. A duct 67 opens into passageway 65 at a point well above the lower curved floor 68 of such passageway. Duct 67 is controlled by a needle valve 69 which in turn may be regulated in any desired manner through an attached head 70. Any overflow of fuel oil from duct 67 will thus tend to accumulate in the lower curved portion 68 of passageway 65. Passageway 65 connects through a port 71 with a horizontal passageway 72 extending to a cylindrical valve casing 73, as best shown in Figs. 3, 5 and 6. The port 71 is normally held closed by a spring-held check valve 74 which may move against the pressure of spring 75 a requisite distance, indicated at 76 in Fig. 5, to permit the desired amount of carbureted gas to enter the passageway 72. The amount of movement of the valve indicated at 76 is controlled by a plug 77, which has a spiral thread 78 in its seat and which is adapted to be rotated by a segment 79 on a pivoted lever 80 controlled by a connection not shown. In this manner the lower end of plug 77 is raised or lowered to permit greater or less opening of valve 74, and the charge going to the engine, as hereinafter appears, will thus be regulated.

Within the casing 73 is a cylindrical valve member 90 which has a closed cap 91 with a stem 92 projecting upwardly therefrom into a socket 93 formed in a cap 94 secured so as to close the top of the casing 73. A sleeve 95 surrounds the cap 94 and has therein a spiral groove 96 adapted to engage lugs 97 on the sides of the pin 92. The sleeve may be rotated by connections with an arm 98, by which means the member 91 may be quickly raised from its normal lowered position, shown in Fig. 5, to a lifted position for a purpose hereinafter to be pointed out. Within the member 90 is a central passageway 99 which curves to one side below cap 91, as indicated at 100, and forms a union with passageway 72. In addition to the central passageway 99 the member 90 is provided with three other passageways 101, 102 and 103, as best shown in Fig. 3. All of these passageways 99, 101, 102 and 103 discharge at their lower ends into a common chamber 104 which is closed at the bottom by a removable screw plug 105 threaded into the valve member 90. The passageway 101 communicates through a port 106 with a horizontal passageway 107 between cylinders 17 and 18, which last-named passageway communicates through ports 108, 109 with the interior of cylinders 17 and 18, as clearly shown in Figs. 3, 5 and 6. Passageways 102, 103 also communicate at their upper ends through ports 110, 111 with the interior of cylinders 17 and 18 at a point nearer the inner or compression end of said cylinder than ports 108, 109, as clearly shown in Fig. 2. The ports 108 and 110 in cylinder 17 are controlled by piston 19 in said cylinder, while the ports 109, 111 in cylinder 18 are controlled by piston 20 in said cylinder 18. Having reference to Fig. 2, wherein piston 19 is moving downwardly on its suction stroke and piston 20 upwardly on its compression stroke, if it be assumed that these pistons have reversed their movement and are approaching the same plane, the one in compression and the other in suction, it will be apparent that at one point the port 110 opening into the chamber 81 above piston 19, and port 111 opening into the chamber 82 above piston 20, will be simultaneously opened, when the compressed gas in one chamber, say chamber 81, will pass through port 110, passageway 102, chamber 104, passageway 103 and port 111 into expansion chamber 82, or vice versa. That is, the gas in the two chambers will be caused to pass through the heated passageways above referred to and be subjected to a change of condition from compression in chamber 81 to vacuum in chamber 82 after port 110 has been closed by continued inward movement of piston 19. Continued downward movement of piston 20 will, of course, increase this vacuum until said piston has uncovered port 109. Air will then pass through port 63, passageway 62, carbureting passageway 65, check-valve-controlled port 71, passageways 72, 99, 101 and 107 and through port 109 into the vacuum chamber 82 above piston 20. Whether or not a sufficient amount of such carbureted air passes to reduce the vacuum in the chamber to atmosphere, or, expressed in other terms, the amount of carbureted air up to that maximum which is permitted to flow, will be determined by the extent of opening of valve 74 permitted by the adjustment of member 77. When the engine is running at maximum capacity and such valve is permitted fully to open, the chamber 82 will be filled so as to reduce the vacuum to atmosphere. Any variation of this amount down to the smallest possible quantity which may be permitted to pass by minimum movement of valve 74 may be effected by the throttling control of said valve member 77.

It is to be noted that the air after it passes the fuel admission duct 67 and becomes charged with the hydrocarbon vapors must pass vertically through passageway 99 into chamber 104, and also that the mixture which is transferred back and forth from chambers 81 and 82 through passageways 102 and 103 are likewise caused to pass vertically downward into the chamber 104. From this it will be seen that any drops or

unvaporized particles of the liquid fuel which may be carried into the apparatus from the primary carburetor will be thrown against the bottom of chamber 104, which accumulations of such drops will continue to be subjected to the currents of air passing back and forth through the passageways as above defined. Such a construction not only effectively prevents the carrying of unvaporized particles of liquid fuel into the cylinder and even prevents the precipitation of heavy particles of dirt or grit, but such unvaporized particles of liquid fuel oil will thereafter be thoroughly vaporized and 10 gasified from the action of the currents of hot gases in the above described passageways and chambers. At the same time the amount of the fresh charge admitted into first one cylinder and then the other, and 15 the consequent amount of charge which is finally forced into the explosion cylinder may be accurately and effectively regulated by the adjustment of valve 74. The chamber 104 may conveniently and easily be 20 cleaned at any time by withdrawing member 90 and removing the closure cap 105. As is shown from an inspection of Fig. 5, this is accomplished by merely unscrewing the cap-piece 83 which closes the top of cylinder 73 and forms the support for the members 94 and 95. The entire valve member 90 may then be withdrawn and closure cap 105 removed and cleaned.

Each of pistons 19 and 20 is provided 35 with a passageway 85 extending downwardly from chambers 81 and 82 and having a port 86 which, at the proper point in the cycle of operations, registers with the opening into passageway 50, so that the charge under compression in either chamber 81 or 40 82 will be forced through passageway 50 into the combustion chamber of one or the other of explosion cylinders 10 or 11 and directed by passageway 50 so as to pass immediately up and across the explosion chamber to spark plug 51. It will be observed 45 from inspection of Fig. 3 that passageway 85 divides adjacent passageway 53, having two branches 87 and 88 which unite below 50 passageway 53 to form the port or passageway 86, which port, like passageway 53, has an opening large enough to register simultaneously with both upper inlet passageways 50 communicating with the respective 55 explosion cylinders 10 and 11.

In general as has already been pointed out, the device operates in the following manner. Referring to Fig. 2, piston 19 is descending and chamber 81 is in partial 60 vacuum. Continued descent of piston 19 opens port 108, which permits the relatively rich and hot gas from passageway 107 to rush into and fill chamber 81 to the extent permitted by the degree of opening of 65 valve 74. At the same time piston 20 will

have moved upward, compressing the gas in chamber 82 so as to open port 86 to passageway 50, as indicated in Fig. 1, and the gas in chamber 82, which is more or less highly compressed according to the charge 70 previously admitted by valve 74, will be driven into the explosion chamber above power piston 13. This charge of gas will increase the compression in explosion chamber 13 over what it would have been had 75 said chamber been filled with an explosive mixture of air and gas at practical atmosphere during exhaust, as is common in the operation of two-cycle engines, and obviously the degree of this compression will be 80 varied according to the volume of gas which has been permitted to pass the valve 74 by reason of the adjustment of the movement of said valve through piece 77. Continued revolution of the crank shafts will reverse 85 the movement of pistons 19 and 20, piston 19 starting to ascend and piston 20 to descend. Upper movement of power piston 13 will, however, after exhaust, have closed port 49 before downward movement of piston 20 has again opened gas port 86 to inlet ports 50. Vacuum will now be produced in chamber 82 and compression of the charge 90 of gas which has passed into chamber 81. When piston 20 uncovers port 111 and thus 95 provides communication between the chambers, the gas under higher pressure in chamber 81 will move into chamber 82 wherein the pressure is relatively lower until the 100 pressures in the two chambers are equalized. Continued movement of piston 19 will close port 110 and consequently change communication between the chambers, whereupon the remaining gas in chamber 81 is subjected to increasing pressure until the 105 port 86 of cylinder 19 opens communication with explosion chamber above piston 12. At the same time the gas in chamber 82 is subjected to an increasing vacuum therein until port 109 is opened by continuous downward movement of piston 20, whereupon 110 charging of chamber 82 with fresh gas, as hereinbefore pointed out, will take place.

The passageway 62 through which the air is delivered to the primary carburetor is 115 highly heated, both by contact with the circulating medium of the cooling system and with the upper walls of the explosion cylinders; and all of the passageways and chambers through which the gas from the 120 primary carburetor must pass before finally reaching the explosion cylinder are also heated. This gas is subject to the long and tortuous line of travel above described with the vertical downward and upward movements through passageways 99 and 101 and passageways 102 and 103, insuring deposit of liquid particles upon the floor and walls of chamber 104 and their subsequent perfect 125 gasification and mixture with the air. The 130

gas is thereafter alternately subjected to vacuum and compression again before final injection into the air-filled explosion chamber. It is thus possible to treat heavy fuel oils from the carburetor and produce an exceedingly rich carbureted mixture to be injected into the explosion chamber in desired quantities, and a mixture in which the hydrocarbons have become volatilized into

10 true gases.

From an inspection of Fig. 2 it will be apparent that in the ordinary operation of the device the maximum charge which can be compressed will have a volume at the common pressure of the gas in the two chambers 81 and 82 equivalent to the volume of said chambers above the inner edge of port 110 or port 111. The density of the gas in this charge will, of course, vary as has been heretofore pointed out by the adjustment of the throttling inlet valve 74, but cannot be greater than the maximum permitted by the adjustment of said valve for maximum opening. It is, however, possible to increase this charge and to correspondingly increase the compression in the explosion cylinder by lifting the valve member 90 through the lever 98 and its connections. Such lifting has the effect of closing

3 ing both of the ports 111 and 110, whereby gas is permitted to flow from chamber 81 to chamber 82, or vice versa, thus giving a maximum charge from chamber 81 or chamber 82 which equals the capacity of such chambers after port 108 or 109 has been fully closed. It is obvious that a plurality of ports such as 110 or 111 may be provided in series one above the other all of which would be controlled by the vertical movement of the valve member 90, in this manner making it practicable to provide two maximum charges for each cylinder, and therefore a plurality of degrees of compression within the explosion chambers. One of the advantages of this method is that the degree of compression may be varied to adapt the engine to operate upon different fuels, a higher degree of compression being desirable for the more volatile fuels such as

50 gasoline, and the lower compression for the heavier fuel oils such as kerosene.

The advantages of my invention will be apparent. The means used to charge the explosion cylinder with air insure a perfect exhaust from said cylinder and the burnt gases will be replaced by air before any of the combustible is introduced into the cylinder. This perfectly insures against waste of fuel. Furthermore, the manner of carrying air through the interior of the power pistons not only has the doubly desirable effect of cooling the piston at a point where it tends to become the hottest, due to its distance from the circulating medium of the cooling system, but also heats the air before

injection into the explosion chamber so that said air will not be cooler than the rich gas mixture which is thereafter forced into the air filled explosion chamber, and there will be no tendency to condensation of the gas 70 and a perfect explosive mixture is formed at high temperature which readily ignites and gives complete combustion and the maximum efficiency of the explosion. Furthermore, the fuel mixture, perfectly carbureted by the means hereinbefore described will always be injected at the right moment and with certainty, so that no matter how rapidly the engine may be run, and notwithstanding that because of its two-cycle operation there will be twice as many explosions in the cylinder in a cycle of operations as is true of the four-cycle engine, there will, nevertheless, always be ample time thus to effect positive and certain charging of the explosion cylinder. Also, the large exhaust area provided by the multiplicity of exhaust ports 43 and extended exhaust manifold 44, which is subjected to the cooling medium on both sides, and the explosive 85 area of the air inlet ports 45 insure removal of burnt gases and charging of the explosive cylinder no matter how rapidly the engine may be running.

95 I claim:

1. An internal combustion engine comprising a casing having therein a power cylinder, a deposit chamber and a multiplicity of passages some of which enter and leave said deposit chamber so that particles 100 of liquid carried through said passageways will be thrown and will gravitate to the walls of said deposit chamber, means for causing explosive mixture to flow through said passageways and deposit chamber, ports 105 through which a portion of the fuel gases is caused to flow back and forth through some of said passageways and the deposit chamber whereby liquid deposit upon the walls thereof will be gasified, and a port 110 through which a portion of the fuel gases is introduced into the power cylinder.

2. An internal combustion engine comprising a casing having therein a pair of power cylinders, a valve chamber fitted 115 with a movable valve, said valve having a central and two side passageways all opening into a common chamber and said casing being provided with a passageway leading to the central passageway in the valve 120 and with two compression chambers each having independent port communication with the respective side passageways, means in the compression chambers for controlling the ports and causing fuel gases to flow into 125 one or the other of said compression chambers through one of said side passageways and for thereafter causing said fuel gases to flow from one compression chamber to the other through the other of said side pas- 130

- 6 sages, and means for admitting a portion of said gases from the compression chamber into its corresponding power cylinder.
3. An internal combustion engine comprising a casing having therein a pair of power cylinders, a valve chamber fitted with a movable valve, said valve having a central and two side passageways all opening into a common chamber and said casing being provided with a passageway leading to the central passageway in the valve and with two compression chambers each having independent port communication with the respective side passageways, means in the compression chambers for controlling the ports and causing fuel gases to flow into one or the other of said compression chambers through one of said side passageways and for thereafter causing said fuel gases to flow from one compression chamber to the other through the other of said side passages, means for admitting a portion of said gases from the compression chamber into its corresponding power cylinder, and means to move the valve so that the ports from the compression chambers to the second of said side passageways will be closed and the fuel gases will be prevented from passing from one compression chamber to the other.
- 30 4. An internal combustion engine comprising a casing having therein a power cylinder, a compression chamber and a passageway leading to the compression chamber, means for drawing fuel gases through said passageway and into the compression chamber, means for regulating the quantity of such fuel gases drawn through the passageway at each stroke of the engine, means for injecting the proportional part of such regulated quantity of fuel gases from the compression chamber into the power cylinder, and means for positively increasing the volume of fuel gases injected into the power cylinder without changing said regulating means.
5. An internal combustion engine comprising a casing having therein two power cylinders and pistons, cranks one hundred and eighty degrees apart for said power pistons, two air pumps, cranks one hundred and eighty degrees apart for said air pumps and arranged so that when the power pistons are at the end of their stroke the pump pistons are substantially at the center of their stroke, and vice versa, and passageways between said power cylinders and said pumps for simultaneously delivering air from both of said pumps to a power cylinder during and after exhaust therefrom.
- 60 6. An internal combustion engine comprising a casing having therein two power cylinders and pistons, cranks one hundred and eighty degrees apart for said power pistons, two air pumps, cranks one hundred and eighty degrees apart for said air pumps and
- arranged so that when the power pistons are at the end of their stroke the pump pistons are substantially at the center of their stroke, and vice versa, and passageways between said power cylinders and said pumps for simultaneously delivering air from both of said pumps to a power cylinder during and after exhaust therefrom. 70
7. An internal combustion engine comprising a casing having therein two power cylinders and pistons, cranks one hundred and eighty degrees apart for said power pistons, two air pumps, cranks one hundred and eighty degrees apart for said air pumps and arranged so that when the power pistons are at the end of their stroke the pump pistons are substantially at the center of their stroke, and vice versa, passageways between said power cylinders and said pumps for simultaneously delivering air from both of said pumps to a power cylinder during exhaust therefrom, means for carbureting air from liquid fuel, and means thereafter operative to force said carbureted air into said power cylinders during the compression stroke. 80
8. An internal combustion engine comprising a casing having therein a pair of power cylinders, means for delivering air to said cylinders during exhaust therefrom, means for carbureting air from liquid fuel, a pair of gas compression cylinders and valve pistons therein, said pistons working in opposite directions to uncover ports connected to a common inlet passageway at one end of their stroke, passageways through which gas is delivered to said power cylinders at the other end of the stroke of said valve pistons, a passageway for gas from one compression cylinder to the other, and means for controlling said passageway. 90
9. An internal combustion engine comprising a casing having therein a pair of power cylinders, means for delivering air to said cylinders during exhaust therefrom, means for carbureting air from liquid fuel, a pair of gas compression cylinders and valve pistons therein, said pistons working in opposite directions to uncover ports connected to a common inlet passageway at one end of their stroke, passageways through which gas is delivered to said power cylinders at the other end of the stroke of said valve pistons, a passageway connecting said compression cylinders, and a valve in said passageway controlling the flow of gas between said compression cylinders. 100
10. An internal combustion engine comprising a casing having therein a power cylinder, a piston in said cylinder, an independent air pump, and means for compelling the air supply to said air pump to pass under the top of the piston for cooling the same. 110
11. An internal combustion engine comprising a casing having therein a power cyl- 120

- inder, a piston in said cylinder, an independent air pump, means for compelling the air supply to said air pump to pass through the piston for cooling the same, and means for 5 scavenging the power cylinder with the air which has passed through said piston.
12. An internal combustion engine comprising a combustion cylinder, a port in said cylinder, a hollow power piston working 10 in said cylinder, said piston being closed at the combustion end, an air port in the wall of said piston, an inwardly projecting enclosure for said air port having its open end extending toward the combustion end of 15 said cylinder, and an independent air pump for drawing air through said port.
13. An internal combustion engine comprising a power cylinder, a piston working in said cylinder, two gas pumps, a piston 20 working in each of said gas pumps, a passageway connecting corresponding ends of said gas pumps, ports controlled by said pistons at different points in their strokes and connected to said passageway, a valve controlling some of said ports and controlling the gas passing through the passageway, a 25 crankshaft for operating said gas pistons one hundred eighty (180) degrees apart, and means for passing gas through said passageway and injecting a controlled amount 30 of gas into the power cylinder.
14. An internal combustion engine comprising a pair of power cylinders, a piston in each of said cylinders, a pair of air pump 35 cylinders, pistons working therein, a pair of pump cylinders, a double acting piston in each of said pump cylinders for pumping air at one end and gas at the other, and a crank shaft for operating each of said 40 pairs of pistons one hundred and eighty degrees apart, the double-acting pistons of the pump cylinders coöperating with the air pump pistons to force air into first one and then the other of said power cylinders.
- 45 15. A two-cycle internal combustion engine comprising an explosion cylinder and a compression cylinder, admission ports to said explosion cylinders communicating with said compression cylinder, a valve piston in 50 said compression cylinder, means for supplying air at one side of said valve piston and explosive mixture gas at the other side of said valve piston, said valve piston opening and closing said admission ports, and 55 means for operating said valve piston for independently injecting the air and explosive mixture separately into the cylinder through the admission ports.
16. A two-cycle internal combustion engine comprising an explosion cylinder and a compression cylinder, admission ports to 60 said explosion cylinders communicating with said compression cylinder, a valve piston in said compression cylinder, means for supplying air at one side of said valve piston 65 and explosive mixture gas at the other side of said valve piston, said valve piston opening and closing said admission ports, and means for operating said valve piston for independently injecting the air and explosive mixture separately into the cylinder through the admission ports.
17. A two-cycle internal combustion engine comprising an explosion cylinder and a compression cylinder, admission ports to 70 said explosion cylinders communicating with said compression cylinder, a valve piston in said compression cylinder, means for supplying air at one side of said valve piston and explosive mixture gas at the other side of said valve piston, said valve piston opening and closing said admission ports, and means for operating said valve piston for independently injecting the air and explosive mixture separately into the cylinder through the admission ports, and means for heating the air and the explosive gas before 75 forcing them into the cylinder.
18. A two-cycle internal combustion engine comprising a compression chamber and a cylinder with two sets of admission ports 80 communicating with said compression chamber, a valve piston in the compression chamber having a passageway adapted to communicate with one of said admission ports during a portion of the stroke of said valve piston, means for supplying air to said compression chamber and means to operate said valve piston whereby said air is forced into the cylinder by the piston through both said 85 sets of admission ports.
19. A two-cycle internal combustion engine comprising a compression chamber and a power cylinder with two sets of admission ports communicating with said compression chamber, a valve piston in the compression chamber having a passageway adapted to communicate with one of said admission ports during a portion of the stroke of said valve piston, a hollow power piston in the cylinder, and means to operate the pistons 90 to cause air to pass beneath and through the power piston and into the compression chamber and to be forced from the compression chamber by the valve piston into the cylinder through both sets of admission 95 ports.
20. An internal combustion engine comprising a power cylinder and a piston operating in said cylinder, an air-pump cylinder and a gas-pump cylinder and a piston 100 operating in each of said cylinders, a power crankshaft connected to the power piston, a pump crankshaft connected to the pump pistons, said pistons arranged so that when the power piston is at the end of its stroke, 105 110 115 120 125 130

the pump pistons are substantially at the center of their stroke, and vice versa, inlet and outlet ports controlled by the power piston, and inlet ports from the gas-pump cylinder to the power cylinder substantially midway of the stroke of the piston in the power cylinder and controlled jointly by the power piston and the gas-pump piston, said gas pump pistons closing said passage-ways during the power stroke of said power pistons.

21. An internal combustion engine comprising a power cylinder and a piston operating in said cylinder, an air-pump cylinder and a gas-pump cylinder and a piston operating in each of said cylinders, a power crankshaft connected to the power piston, a pump crankshaft connected to the pump pistons, said pistons arranged so that when the power piston is at the end of its stroke, the pump pistons are substantially at the center of their stroke, and vice versa, inlet and outlet ports controlled by the power piston, and inlet ports from the gas-pump cylinder to the power cylinder substantially midway of the stroke of the piston in the power cylinder and controlled jointly by the power piston and the gas-pump piston, said ports being uncovered by the power piston near the center of its expansion stroke and held closed by the pump piston at the end of its suction stroke.

22. An internal combustion engine comprising a power cylinder and a piston operating in said cylinder, an air-pump cylinder and a gas-pump cylinder and a piston operating in each of said cylinders, a power crankshaft connected to the power piston, a pump crankshaft connected to the pump pistons, said pistons arranged so that when the power piston is at the end of its stroke, the pump pistons are substantially at the center of their stroke, and vice versa, inlet and outlet ports controlled by the power piston, and inlet ports from the gas-pump cylinder to the power cylinder substantially midway of the stroke of the piston in the power cylinder and controlled jointly by the power piston and the gas-pump piston, said ports being closed by the power piston near the center of its com-

pression stroke and opened by the pump piston at the end of its compression stroke.

23. An internal combustion engine comprising a power cylinder and a piston operating in said cylinder, an air-pump cylinder and a gas-pump cylinder and a piston operating in each of said cylinders, a power crankshaft connected to the power piston, a pump crankshaft connected to the pump pistons and operating said pistons so that when the power piston is at the end of its stroke, the pump pistons are substantially at the center of their stroke, and vice versa, inlet and outlet ports controlled by the power piston, air and gas inlet ports to the power cylinder jointly controlled by the power piston and the pump piston so that air is admitted to the power cylinder at the end of the stroke of the power piston and gas is admitted to the power cylinder at the end of the stroke of the pump piston, and inlet ports from the gas-pump cylinder to the power cylinder substantially midway of the stroke of the piston in the power cylinder and controlled jointly by the power piston and the gas-pump piston.

24. An internal combustion engine comprising two power cylinders, a piston in each of said cylinders working in opposite directions to each other, two air pump cylinders, a piston in each of said cylinders for pumping air to said power cylinders and working in opposite directions to each other and timed so that said last-mentioned pistons are at the end of their stroke when the power pistons are at the center of their stroke, two gas-pump cylinders, pistons working therein conjointly with the air-pump pistons, each of said gas pistons admitting gas to the gas-pump cylinders at the end of one stroke and admitting gas to a power cylinder at the end of the succeeding stroke, a passageway for gas from one gas-pump cylinder to the other, and means for controlling said passageway.

In testimony whereof I affix my signature in presence of two witnesses.

JAMES JESSEN.
